Patented Jan. 6, 1976

238,362

FISHING SIGNAL DEVICE

Lawrence L. Muehl and Theodore Montgomery, Frankfort, S. Dak., assignors to Dakota Cateye, Inc., Frankfort, S. Dak.

Filed July 24, 1974, Ser. No. 491,396

Term of patent 14 years

Int. Cl. D22—05

U.S. Cl. D22—13

Fig. 1.

Fig. 2.

Fig. 3.

Fig. 4.

Fig. 5.

FIG. 1 is a side elevational view of a fishing signal device showing our new design;

FIG. 2 is a rear elevational view;

FIG. 3 is a side elevational view opposite to that shown in FIG. 1;

FIG. 4 is a bottom plan view thereof; and

FIG. 5 is a rear elevational view of a fishing signal device.

We claim:

The ornamental design for a fishing signal device, as shown.
